UNITED STATES PATENT OFFICE.

HARRY A. DAVOL, OF METHUEN, MASSACHUSETTS, ASSIGNOR TO U. S. BOBBIN & SHUTTLE CO., OF PROVIDENCE, RHODE ISLAND, A CORPORATION OF RHODE ISLAND.

FRICTION DEVICE FOR SHUTTLES.

Application filed April 19, 1927. Serial No. 185,001.

This invention is a friction device for shuttle threader blocks such as are used in shuttles, particularly those of the self threading type.

5 It is particularly useful because of the compactness and ready adjustability of its parts whereby in the same shuttle very fine, fragile yarn or thread can be used, or relatively coarse strong thread. If any of the 10 parts break or become useless, in most cases they can be removed without taking the shuttle block out of the shuttle, but in every case all of the friction parts on which there is any 15 wear can be readily removed and replaced by others.

I am aware that there are a number of friction devices which include friction plates, a spring and an adjusting screw but I believe my device is simpler, more easily repaired 20 and less likely to get out of order than any others.

In the drawings, Fig. 1 is a plan view of a shuttle with my device in place, part being broken away to show the construction.

25 Fig. 2 is an elevation of a shuttle block with my device shown as removed from the shuttle, viewed from the side opposite the shuttle eye.

Fig. 3 is a front elevation as from the left 30 of Fig. 2.

Fig. 4 is a view similar to Fig. 2 showing a slight modification.

Fig. 5 is a view similar to Fig. 2 of a modification.

35 In the accompanying drawings W indicates the body of a shuttle having a bobbin recess 1 in which is positioned the bobbin B of the usual kind and from which the thread Y extends through the threader block R in substantially the usual manner. There is the 40 usual threading chamber 4 in the wood, and the corresponding threading chamber 5 in the threading block.

In the types shown in Figs. 1 to 4 the top 45 20 of this block R serves as a guide and slopes downward at 21 to a front guide 23, and at the back to a back hook or back guide 22 in a well known manner, and across and down over the longitudinal middle line of the shuttle.

The horn 32 is of the usual construction

and the thread pin 30 may be vertical or may slope down and back to help keep the yarn down on the friction pin such as F which serves as a bottom friction device. The pin 55 F may be of hard steel or a cylindrical piece of glass, felt or in fact any other suitable material extending transversely across the lower part of the threader block through the hole 24 which as shown is directly under the 60 threaded screw pin head hole 25.

It is obvious that when this friction pin F becomes worn at the top, it can be taken out and replaced by another merely by removing the threader block and knocking it out, or it 65 may be knocked out and turned and then replaced.

The top friction is a plate H, preferably of sheet metal, which is flat at the bottom, and there rests on friction pin F and then extends 70 toward the side where its horizontal edge 40 is preferably straight so that it can slip up and down along the side wall 29 of threading chamber 5 in block R.

Through plate H there is a tension screw 75 pin hole 45 which registers with pin head hole 25.

Tension screw pin A has a threaded head 50 which is screwed into the pin head hole 25, and a reduced shank 51 which is preferably of hardened steel and passes down through hole 45. This screw pin A is encircled by tension spring B between its head 50 and the top of the friction plate H. By turning this screw pin A, the tension on 85 spring B can be altered as desired. Preferably the bottom end of screw pin A extends into a hole 46 in the bottom friction pin F.

Friction plate H has an upwardly extending guide tongue 43 which extends from the 90 forward part of its side edge up and in between the front hook or guide 23 and the back hook or guide 22 in such a manner that it keeps the thread away from spring B and from being entangled therein.

I prefer to strengthen my friction block by forming an integral sleeve 11 around the attaching bolt hole 12. This also serves the purpose of lifting up the thread and helping to guide it between the friction plate and 100 the friction pin.

I can make a close joint between the fric-

tion plate H and the friction pin F as shown in Fig. 4, so that a slub indicated at 100 will be caught and the thread broken.

In Fig. 5, I show a threader block R having a top 101 which terminates at the front in a guide or nose 102 but along the back side edge 103 has substantially no back guide nor back guide hook.

The friction plate M is substantially curved up at the exposed side and has sides 184 and 185, but its base 183 is wide enough to allow two locking teeth 187, 187 to project down on each side of friction pin F.

I can use one pin with a tooth each side but I prefer to use two pins preferably of glass or hardened steel with a tooth between them, because if one side of the friction plate jumps the other remains in contact with the other pin.

20. This is important especially with rayon thread which may be one two-thousandth of an inch in thickness but which has a tendency to wave if there is not a steady regular friction.

25. It is desirable that the front guide 102 should direct the thread down onto the horn 32 and that the top 101 should slope down and across the axial line of the shuttle and that the back side edge 103 should be so made 30 as to throw any loop down below the top 83 of friction plate L.

While I prefer to have the side edge of the friction plate in contact with the vertical side wall for a substantial distance, the principal 35 purpose is to prevent the plate from turning and it is sufficient if any part of the side edge will engage the side wall and act as a stop to prevent the friction plate from turning.

I may also utilize teeth such as 187, 187 on 40 each side of the friction pin located between the screw pin A and the side wall such as 29 or at the opposite side of the screw pin, to prevent turning. This is objectionable because they might jump up and wiggle or crawl 45 up over the friction pin.

I therefore prefer to locate teeth on the side of the screw pin opposite the wall 29, in such position that the thread must pass down under them in getting into position. They 50 serve to lock it in place and prevent it from slipping out.

This is particularly desirable with rayon or other similar very fine, wiry thread which has a tendency to kink.

55. I claim:

1. The combination in a threading block for shuttles in which there is a threading chamber having one substantially vertical side wall, a top guide which extends downward into said chamber, and a vertical threaded screw pin head hole; of a friction pin which extends across the bottom of the threading chamber and which has a flattened top face; a friction plate which rests on the

friction pin, said friction plate having a side 65 edge in contact with said vertical side wall, a curved upwardly projecting guide tongue positioned forward of the screw pin between the front and back of the top guide and a tension screw pin hole; a screw pin having a threaded head which is screwed into the screw pin head hole and a shank which passes through the screw pin hole in the friction plate; and a tension spring which surrounds the shank of the screw pin between its head 70 and the friction plate. 75

2. The combination in a threading block for shuttles in which is a threading chamber having one substantially vertical side wall, and a vertical threaded screw pin head hole; 80 of a friction pin which extends across the bottom of the threading chamber; a friction plate which rests on the friction pin, said friction plate having a side edge in contact with said vertical side wall, a curved upwardly projecting guide tongue and a tension screw pin hole; a screw pin having a threaded head which is screwed into the screw pin head hole and a shank which passes through the screw pin hole in the friction plate; and a tension spring which surrounds the shank of the screw pin between its head and the friction plate. 85

90 3. The combination in a threading block for shuttles in which is a threading chamber having a side wall and a screw pin head hole; 95 of a friction pin which extends across the bottom of the threading chamber; a friction plate in operative relation with and proximate to the friction pin, said friction plate 100 having an edge in contact with the said side wall, a curved upwardly projecting guide tongue and a tension screw pin hole; a headed screw pin which engages the screw pin head hole and which passes through the pin 105 hole in the friction plate; and a tension spring which surrounds the shank of the screw pin between its head and the friction plate.

4. The combination in a threading block for shuttles in which is a threading chamber 110 having a side wall and a screw pin head hole; of a friction pin which extends across the bottom of the threading chamber; a friction plate in operative relation with and proximate to the friction pin, said friction plate 115 having a thread holding tooth in its bottom, an edge in contact with the said side wall, a curved upwardly projecting guide tongue and a tension screw pin hole; a headed screw pin which engages the screw pin head hole 120 and which passes through the pin hole in the friction plate; and a tension spring which surrounds the shank of the screw pin between its head and the friction plate.

5. The combination in a threading block 125 for shuttles in which is a threading chamber having a side wall and a screw pin head hole; of a friction pin which extends across the

bottom of the threading chamber; a friction plate in operative relation with and proximate to the friction pin, said friction plate having an edge in such relation to said side wall that it acts as a stop to prevent the friction plate from revolving, a curved upwardly projecting guide tongue and a tension screw pin

hole; a headed screw pin which engages the screw pin head hole and which passes through the pin hole in the friction plate; and a tension spring which surrounds the shank of the screw pin between its head and the friction plate.

HARRY A. DAVOL.
